[57] CLAIM

The ornamental design for a weatherproof padlock cover, as shown and described.

DESCRIPTION

FIG. 1 is top, front, and right side perspective view of a weatherproof padlock cover showing my new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The broken-line disclosure of a padlock shackle in the views is for illustrative purposes only and forms no part of the claimed design.
